UNITED STATES PATENT OFFICE.

WALTER R. WILSON, OF WARREN, OHIO.

ANNEALING-BOX.

1,180,095.

Specification of Letters Patent. Patented Apr. 18, 1916.

Application filed February 20, 1915. Serial No. 9,640.

To all whom it may concern:

Be it known that I, WALTER R. WILSON, of Warren, in the county of Trumbull and State of Ohio, have invented certain new and useful Improvements in Annealing-Boxes; and I do hereby declare the following to be a full, clear, and exact description of the invention, such as will enable others skilled in the art to which it appertains to make and use the same.

The object of this invention is to provide an improved and highly-efficient annealing box of maximum durability, the box being so constructed as to permit of the greatest amount of expansion and contraction of its confining walls in every direction without danger of cracking, there being no straight lines in any wall.

In the accompanying drawing, Figure 1 is a side elevation. Fig. 2 is a sectional view on line 2—2, Fig. 1. Fig. 3 is a top plan view. Fig. 4 is a fragmentary sectional view on line 4—4, Fig. 1. Fig. 5 is an enlarged fragmentary view. Fig. 6 is a dia-

grammatic view.

In the drawings I have shown the box as being of rectangular form, the side walls 1 and 2 being integral, and two of the side walls provided with the usual trunnions 3. The walls and the top are so formed as to allow of maximum expansion and contraction at all points, no part of the inner or outer surfaces presenting an extended uninterrupted plane. This I attain by forming in the walls and top parallel rows of outwardly-extending spaced-apart bulges 4, and intermediate these rows I form spaced depressions 5, the bulges and depressions being in staggered or broken joint arrangement, that is, intersecting each other on ob-

lique lines. The bulges 4 are separated on vertical and horizontal lines by swellings 6 of concavo-convex formation, the concavities taking form from the inward sloping of the bulges 4 on vertical and horizontal lines, 45 and the convexities by the swellings between the depressions on like lines.

As shown in Fig. 2, the inner faces of the walls and top are formed similarly to the outer faces, the depressions 5 of the latter 50 forming the inwardly-extending bulges 4' and the bulges 4 of the outer face the depressions 5' of the inner, the spacings between these parts corresponding to the described formation relative to the outer face. 55

It will be apparent that the walls and top of the box are so formed that every line and angle is sinuate, thus providing the greatest possible surface for expansion and contraction and preventing cracking of the metal, 60 there being no straight lines liable to give under stress.

I claim as my invention:

An annealing box comprising an integral structure having its walls formed with parallel rows of outwardly and inwardly bulged portions, those of one row being in staggered or broken joint arrangement relatively to those of an adjacent row, the spaces between the outwardly bulged portions of adjacent 70 rows and between the intermediate inwardly bulged portions being concavo-convexed.

In testimony whereof, I have signed this specification in the presence of two subscribing witnesses.

WALTER R. WILSON.
